SWITCHING APPARATUS

Hans Sengebusch, Villa Park, Ill., assignor to
 Associated Electric Laboratories, Inc., Chicago,
 Ill., a corporation of Delaware

Application June 20, 1938, Serial No. 214,721

41 Claims. (Cl. 179—27.52)

The present invention relates to switching apparatus and more particularly to improvements in switching apparatus of the form suitable for use in automatic telephone exchanges.

5 In an automatic telephone exchange, one of the major items of cost, both in the installation and in the maintenance thereof, is the multiples extending between the bank contacts of the various automatic switches. Switching apparatus 10 comprising a plurality of automatic switching units and an associated conductor bank formed of uninsulated conductors which serve both as multiple conductors between the plurality of switching units and as wiper contacts 15 for the wipers of the individual switching units has been proposed in order to reduce the item of cost mentioned above. In switching apparatus of this type, the individual automatic switching units conventionally employed are of considerable 20 size and of complicated construction, thereby detracting from the inherent economy of the apparatus.

Accordingly, it is an object of the present invention to provide an improved switching unit 25 adapted to be used in conjunction with a bare wire bank contact and multiple field which is compact and economical to manufacture, simple in arrangement, positive in operation, and includes a minimum number of parts.

30 In general the object set forth above is attained in accordance with the present invention by providing a switching unit which comprises a plurality of elementary switches; each of the elementary switches including a carriage 35 movable in a first direction, an element carried by the carriage and movable in a second direction and a contact controlling member carried by the element; means for selecting any one of the elementary switches to be operated; means 40 including a first operating member common to the elementary switches for moving the carriage of a selected one of the elementary switches; and means including a second operating member 45 common to the elementary switches for moving the element of the selected elementary switch.

More specifically, the first operating member is supported for both rotational and longitudinal step-by-step movement and the second operating member is supported for rotational step-by-step movement. The rotational step-by-step movement of the first operating member is effective to select successively the elementary switches to be operated, while the longitudinal step-by-step movement of the first operating member is 55 effective to move the carriage of a selected one

of the elementary switches step by step in the first-mentioned direction. The rotational step-by-step movement of the second operating member is effective to move the element of the selected elementary switch step by step in the 5 second-mentioned direction.

In accordance with a further feature of the invention, an improved arrangement is provided for operating and controlling the switching unit, which comprises a mechanism selectively operable to impart to the first operating member both rotational and longitudinal step-by-step movements and to impart to the second operating member rotational step-by-step movement, means for controlling the selective operations 15 of the mechanism and means including a locking mechanism for controlling the movements imparted to the first operating member.

The novel features believed to be characteristic of the invention are set forth with particularity in the appended claims. The invention, both as to its organization and method of operation, together with further objects and advantages thereof, will best be understood by reference to the following specifications taken in connection with accompanying drawings, in which Fig. 1 is an end elevational view of the front and rear frames of switching apparatus having embodied therein a plurality of switching units constructed and arranged in accordance with 20 the present invention; Fig. 2 is a side elevational view of the front frame shown in Fig. 1; Fig. 3 is an enlarged side elevational view, partly in section, of a particular structural detail of the front frame, taken in the direction of the 25 arrows 3 in Fig. 1; Fig. 4 is an enlarged sectional view of the particular structural detail of the front frame, taken along the line 4—4 in Fig. 2; Figs. 5A and 5B, taken together, are a fragmentary plan view of one of the automatic 30 switching units of the switching apparatus; Fig. 40 6 is an end elevational view of the switching unit shown in Figs. 5A and 5B; Fig. 7 is a side elevational view of the switching unit; Fig. 8 is a diagrammatic illustration of the arrangement 45 of the cam members in a lock and clutch control mechanism embodied in the switching unit; and Fig. 9 is an enlarged fragmentary end elevational view of the conductor bank and two of the switching units carried by the front and rear 50 frames, shown in Fig. 1.

Referring now more particularly to Figs. 1 and 2 of the drawings, there is illustrated switching apparatus including front and rear frames 55 20 and 21, respectively, the frames being of simi-

lar construction and each comprising a plurality of vertical and horizontal members 22 and 23, respectively, secured together in any suitable manner. The frames 20 and 21 are arranged back to back and secured together in spaced relation, a conductor bank 24 being arranged to occupy the space between the backs of the frames. The conductor bank 24 comprises a plurality of vertically disposed conductors divided into ten spaced-apart groups; each group comprising ten subgroups or levels; each subgroup comprising ten lines; and each line including a positive and a negative conductor. Also each line may be provided with a control or private conductor in the event the switching apparatus is utilized in a telephone system wherein each line circuit includes a control or private conductor. Each conductor in each group in the conductor bank 24 is uninsulated and serves both as a multiple conductor between the switching units and as a wiper contact for the wipers of the individual switching units. Also, each conductor is retained in position in its group by a plurality of spaced-apart insulating members 25. The positive and negative line conductors in each group in the conductor bank 24 are segregated into two spaced-apart divisions which are arranged in the same manner. The line conductors in each subgroup in both the positive and negative divisions are arranged in substantially the same vertical plane, each line conductor being spaced from the adjacent line conductor by a fixed distance; and the subgroups in each group are arranged in substantially parallel vertical planes, each subgroup being spaced from the adjacent subgroup by a fixed distance.

Each of the frames 20 and 21 is adapted to support a group of identical automatic switching units in vertical alignment and in such a manner that each switching unit has access to each line in the conductor bank 24. This is accomplished by providing the front frame 20 with a plurality of sets of supported elements 26 and the rear frame 21 with a plurality of sets of supporting elements 27. In each frame each set of supporting elements is spaced in a vertical direction a fixed distance from the adjacent set of supporting elements and comprises two horizontally aligned supporting elements respectively secured to the vertical members 22 disposed at the right-hand and left-hand ends of the frame. In order to prevent the switching units supported by the rear frame 21 from interfering with the switching units supported by the front frame 20, the sets of supporting elements 27 carried by the rear frame 21 are staggered in a vertical direction with respect to the sets of supporting elements 26 carried by the front frame 20. Thus, the switching units in one of the groups have access to sections of the conductor bank 24 disposed between the switching units of the other group, as illustrated in Fig. 9.

Each switching unit is provided with a base plate 28 which constitutes a shelf adapted to be supported upon one of the sets of supporting elements carried by one of the frames. As best shown in Figs. 3 and 4, the opposite ends of the base plate 28 of one of the switching units supported in the front frame 20 rest upon the upper surfaces of the supporting elements of one of the set of supporting elements 26. The base plate 28 is provided with an upstanding flange 29 extending along the front edge thereof which projects over the vertical members 22 disposed at the opposite ends of the front frame 20. The base plate

28 is secured in place at each end thereof by an arrangement including a screw 30 extending through an elongated opening 31 formed in the flange 29 and threaded into an opening in the vertical member 22. Also an arrangement is provided for locking each end of the base plate 28 securely in place, which comprises a pair of screws 32 threaded in openings formed in the flange 29 and engaging the vertical member 22. The elongated openings 31 formed in the opposite ends of the flange 29 accommodate adjustment of the switching unit in a longitudinal direction with respect to the ends of the front frame 20, and the screws 30 and 32 accommodate adjustment of the switching unit in a lateral direction with respect to the front and back of the front frame 20.

In placing a switching unit in the front frame 20 the base plate 28 of the switching unit is first positioned upon the set of supporting elements 26 disposed at the desired level. The switching unit is then slid laterally into place and adjusted so that the same is in proper alignment with respect to the conductor bank 24. The screws 30 are then inserted through the elongated openings 31 formed in the opposite ends of the flange 29 and tightened into snug engagement with the flange 29. The screws 32 are then tightened into snug engagement with the vertical members 22 disposed at the opposite ends of the front frame 20, thereby securely retaining the switching unit in its adjusted position. The switching unit may be removed from the front frame 20 by withdrawing the base plate 28 after the screws 30 have been untightened and removed.

Referring now to Figs 5A, 5B, 6 and 7, there is shown a fragmentary portion of one of the automatic switching units of the switching apparatus, which comprises ten elementary switches of identical construction respectively associated with the ten groups of lines in the conductor bank 24; the illustrated elementary switches 33, 34 and 35 being associated respectively with the first, second and tenth levels or groups of lines in the conductor bank 24. Each of the elementary switches 33, 34 and 35 comprises a carriage 36 individually provided with an element or slide 37, upon which a contact controlling member 38 is mounted. The contact controlling member 38 carries two pairs of wipers or contact members 39 and 40, respectively associated with the positive and negative divisions of the line conductors in the associated group of lines in the conductor bank 24. A terminal block 41 is also mounted on the slide 37 in order to extend electrical connections to the pairs of contact members 39 and 40. The carriage 36 of each elementary switch is slidably mounted on two substantially parallel longitudinal guide bars 42 and 43, which are supported by two spaced apart brackets 44 and 45 carried by the base plate 28. Each of the carriages 36 is biased to a normal position and movable along a longitudinal path into ten off-normal positions respectively corresponding to the ten subgroups or levels in the associated group of lines in the conductor bank 24. The slide 37 of each elementary switch is biased to a normal position and movable along a lateral path into ten off-normal positions respectively corresponding to the ten lines in each subgroup or level in the associated group of lines.

An arrangement including an operating member or shaft 48, common to the elementary switches and mounted for both rotational movement and movement in a longitudinal direction, is provided for selecting the particular elementary

switch to be operated, and for moving the carriage 36 of the selected elementary switch into any one of its ten off-normal positions. The operating shaft 48 is biased to a normal angular position and rotatable in a counterclockwise direction, as viewed from the left-hand end thereof, into ten off-normal angular positions; and biased to a normal longitudinal position and movable toward the left into ten off-normal longitudinal positions.

More particularly, the operating shaft 48 is rotatably and slidably supported in bearings provided in the brackets 44 and 45 and a bracket 49 carried by the base plate 28. The operating shaft 48 carries ten cam members respectively associated with the ten elementary switches, the illustrated cam members 50, 51 and 52 being respectively associated with the elementary switches 33, 34 and 35. Each of the cam members is provided with a first part or projection which is adapted to be moved into driving relationship with a second part or slot formed in the carriage of the associated elementary switch, the cam members 50, 51 and 52, respectively, being provided with projections 50^a, 51^a, and 52^a which are adapted respectively to be moved into slots 50^b, 51^b, and 52^b formed in the carriages of the elementary switches 33, 34 and 35, respectively. The cam projections 50^a, 51^a, etc., are successively displaced by a fixed angular distance about the operating shaft 48 and arranged in such a manner that the cam projection 50^a is moved into the slot 50^b formed in the carriage 36 of the elementary switch 33, when the operating shaft 48 is rotated from its normal angular position into its first off-normal angular position; that the cam projection 50^a is moved out of the slot 50^b and the cam projection 51^a is moved into the slot 51^b formed in the carriage 36 of the elementary switch 34, when the operating shaft 48 is rotated into its second off-normal angular position; etc. When the cam projection 50^a occupies a position in the slot 50^b, the carriage 36 of the elementary switch 33 is locked to the operating shaft 48 for movement in a longitudinal direction therewith, thereby rendering the elementary switch 33 operative to select a line from the first group of lines in the conductor bank 24. In a similar manner, the carriage of any one of the other elementary switches may be locked to the operating shaft 48, thereby rendering the one elementary switch operable to select a line from the associated group of lines in the conductor bank 24. The arrangement of the cam members 50, 51, 52, etc., on the operating shaft 48 permits only one of the elementary switches to be rendered operable or to be selected at any time; and any one of the elementary switches may be selected to be operated by rotating the operating shaft 48 to a corresponding off-normal angular position. At this time, the operating shaft 48 is retained in any predetermined off-normal angular position by an arrangement described subsequently.

After the operating shaft 48 has been rotated into a predetermined off-normal angular position to cause a corresponding elementary switch to be selected and locked to the operating shaft 48 for movement in a longitudinal direction therewith, the operating shaft 48 is moved from its normal longitudinal position into a predetermined off-normal longitudinal position, causing the carriage of the selected elementary switch to be moved toward the left into a corresponding off-normal position, thereby to select a corresponding subgroup or level from the associated group of lines.

The carriage 36 of the selected elementary switch

is moved longitudinally against the bias of a coil spring 68 individual thereto, one end of the spring being secured to a lug 66 provided on the carriage 36, and the other end thereof being secured to a screw 57 carried by the base plate 28. At this time, the operating shaft 48 is retained in its predetermined off-normal longitudinal position by an arrangement including a ratchet 53 provided on the extreme right-hand end of the operating shaft 48 and an associated detent 54 pivotally mounted upon the guide bar 43; the carriage 36 of the operated elementary switch being retained in its predetermined off-normal position by the engagement between the projection on the cam carried by the operating shaft 48 and the slot formed in the carriage of the operated elementary switch. Also, an additional arrangement including a locking member or bar 37^a, individual to the operated elementary switch, is provided for retaining the carriage 36 thereof in its predetermined off-normal position independently of the position of the operating shaft 48. Ten spaced apart notches are formed in the locking bar 37^a and correspond to the ten off-normal positions of the carriage 36, the notches being adapted to engage a downwardly extending flange or member provided on the slide 37 carried by the carriage 36.

An arrangement including an operating member or shaft 58, common to the elementary switches and mounted for rotational movement, is provided for moving the slide 37 of a selected elementary switch in a lateral direction into any one of its ten off-normal positions. The shaft 58 is of tubular construction, having stub shafts 59 and 60 secured in the opposite ends thereof, the stub shafts 59 and 60 being rotatably supported in bearings provided in the brackets 44 and 45, respectively. The operating shaft 58 is biased to a normal position, and is rotatable in a counter-clockwise direction, as viewed from the left-hand end thereof, into ten off-normal positions against the bias of a coil spring 68. The spring 68 encloses the extreme right-hand end of the stub shaft 60, one end of the spring 68 being secured in a notch 60^a formed in the stub shaft 60, and the other end thereof being secured to the bracket 45. The operating shaft 58 carries ten cylindrical gears respectively associated with the slides carried by the ten elementary switches, the illustrated gears 61, 62 and 63 being associated with the slides 37 carried by the elementary switches 33, 34 and 35, respectively. As best shown in Fig. 7, the slide 37 of each elementary switch is of substantially channel shape having two downwardly extending flanges 64 and 65, and is retained in position by a bracket 66 secured to the carriage 36. The flange 64 of the slide 37 is provided with a plurality of teeth 67 which are adapted to engage the associated cylindrical gear carried by the operating shaft 58, thereby rendering the slide 37 a rack operated by the associated cylindrical gear.

When the carriage 36 of a selected elementary switch is moved to a predetermined off-normal position, thereby to select a corresponding subgroup or level in the associated group of lines, the teeth 67 provided in the slide 37, carried by the carriage 36, are brought into engagement with the associated cylindrical gear carried by the operating shaft 58. The operating shaft 58 is then rotated from its normal position into a predetermined off-normal position, causing the slide 37, carried by the carriage 36 of the selected elementary switch, to be moved into a corresponding off-normal position, due to the driving engage-

ment between the cylindrical gear and the associated slide, thereby to cause the pairs of contact members 39 and 40 to select a corresponding line from the previously selected subgroup or level 5 in the associated group of lines. The pairs of contact members 39 and 40 respectively engage the positive and negative conductors of the selected line, a connection being extended thereto by way of the terminal block 41. When the operating shaft 58 is rotated into its first off-normal position, the slide 37 is moved into its first off-normal position. At this time, the forward edge 10 of the flange 64 on the slide 37 engages one of the notches formed in the locking bar 37^a and corresponding to the particular off-normal position 15 of the carriage 36. The engagement between the slide 37 and the locking bar 37^a retains the carriage 36 in its predetermined off-normal position independently of the position of the operating shaft 48. Also, at this time, a lug, not shown, carried by the under side of the operating shaft 58, engages the detent 54 pivotally mounted on the guide bar 43, causing the detent to be moved 20 out of engagement with the ratchet 53, thereby to release the operating shaft 48 for movement in 25 a longitudinal direction back into its normal longitudinal position. The operating shaft 48 is subsequently rotated back into its normal angular position, and moved longitudinally back into its 30 normal longitudinal position by an arrangement described subsequently.

In the selected elementary switch, the slide 37 is retained in its predetermined off-normal position by the operating shaft 58, the operating shaft 58 being retained in its predetermined off-normal position by an arrangement described subsequently. The carriage 36 of the selected elementary switch is retained in its predetermined off-normal position by the engagement between 40 the slide 37 and the locking bar 37^a. In order to restore the operated elementary switch to its idle position, the arrangement for retaining the operating shaft 58 in its predetermined off-normal position is released, causing the spring 68 to rotate the operating shaft 58 in a clockwise direction back into its normal position. As the operating shaft 58 is rotated back into its normal position, the slide 37 is moved back into its normal position, due to the driving connection between 45 the cylindrical gear carried by the operating shaft 58 and the slide 37. When the slide 37 is moved back into its normal position, the flange 64 thereon disengages the notch in the locking bar 37^a, and the carriage 36 is moved back 50 into its normal position by the spring 55.

In order to control the operating shafts 48 and 58 in the switching unit, in the manner previously described, an arrangement including an operating motor 69 and a lock and clutch control mechanism 70 is provided. The operating motor 69 is of the electromagnetic type, comprising a frame 71, secured to the base plate 28 by a plurality of screws 72, and a pivotally mounted armature 73 provided with an outwardly extending arm 74 adapted to carry a pawl, not shown, arranged in driving relationship with a ratchet wheel 75. The ratchet wheel 75 is mounted for rotation upon a rotatable shaft 76, which is supported in a pair of spaced apart bearing housings 77 carried by a bearing bracket 78, secured to the base plate 28 by a plurality of screws 79. The ratchet wheel is rigidly secured to a clutch member 80, which carries two clutch plates 81 and 82 on the opposite ends 75 thereof. The clutch member 80 is so construct-

ed and arranged that it is rotated step by step in a counter-clockwise direction, as viewed from the left-hand end thereof, by the ratchet wheel 75 and the operating motor 69. The clutch plates 81 and 82, carried on the opposite ends of the clutch member 80, are arranged respectively to drive two cooperating clutch plates 83 and 84, the clutch plates 83 and 84 being rigidly secured respectively to the shaft 76 and the stub shaft 59. The clutch plates 81 and 83 constitute a driving arrangement for rotating the shaft 76 step by step in a counter-clockwise direction, while the clutch plates 82 and 84 constitute a driving arrangement for rotating the operating shaft 58 step by step in a counter-clockwise direction. The shaft 76 is normally biased to a predetermined angular position by a coil spring 85. The coil spring 85 encloses the extreme left-hand end of the shaft 76, one end of the spring 85 being secured in a notch 76^a, formed in the left-hand end of the shaft 76, and the other end thereof being secured to the base plate 28. Also, a gear 86 is rigidly secured to the shaft 76 and engages a gear 87 rigidly secured to a rotatable shaft 88, which latter shaft is supported in two spaced apart bearing brackets 90 carried by the base plate 28. Also, a spiral gear 91 is rigidly secured to the shaft 88 and engages a cylindrical spiral gear 92 rigidly secured to the operating shaft 48. The gears 86 and 87, the spiral gear 30 91, and the cylindrical spiral gear 92 constitute a driving arrangement for imparting both rotational and longitudinal step-by-step movements to the operating shaft 48.

The lock and clutch control mechanism 70 35 comprises a ratchet wheel 93 and two substantially disc-shaped cam members 94 and 95 rigidly secured to a rotatable shaft 96, which is carried by the base plate 28. The ratchet wheel 93 is arranged to be driven by a pawl 97 pivotally mounted on an arm 98, carried by a pivotally mounted armature 99 of an operating motor 100. The operating motor 100 is of the electromagnetic type and includes a frame 101 carried by the base plate 28. The arm 98 is normally biased 40 away from the ratchet wheel 93 by a leaf spring 102 and into engagement with a stop 103 carried by the base plate 28, the leaf spring 102 being secured to the base plate 28 by a plurality of screws 104. The pawl 97 is biased toward the ratchet wheel 93 by a coil spring 105 extending 45 between the pawl 97 and the arm 98. The periphery of the cam member 94 is provided with a plurality of projections 94^a, which are spaced apart by intervening depressions 94^b. Associated 50 with the cam member 94 is a clutch control lever 106, provided with two outwardly extending arms 107 and 108. The clutch control lever 106 is pivotally mounted intermediate the ends of the arms 107 and 108 upon a shaft 109, carried by 55 the base plate 28, and is biased in a clockwise direction by a coil spring 110 extending between the arm 108 and the bracket 44. The extreme outer end of the arm 107 is provided with a finger 111 which rides upon the periphery of the 60 cam member 94, while the extreme outer end of the arm 108 is provided with a tab 112 which is disposed in an annular recess 80^a formed in the clutch member 80 between the clutch plates 81 and 82 and the ratchet wheel 75. The lock and clutch control mechanism 70 is so constructed and arranged that it is rotated step by step in a counter-clockwise direction by the ratchet wheel 93 and the operating motor 100. As the lock and clutch control mechanism 70 is rotated step by 70 75

step, the finger 111 on the arm 107, riding upon the periphery of the cam member 94, alternately engages one of the projections 94^a and one of the depressions 94^b, disposed about the periphery 5 of the cam member 94. When the finger 111 engages one of the projections 94^a, the clutch control lever 106 is rotated in a counter-clockwise direction about the shaft 109 against the bias of the spring 110, causing the tab 112 on the arm 108 to move the clutch member 80 toward the left, thereby to engage the clutch plates 81 and 83. On the other hand, when the finger 111 engages one of the depressions 94^b, the clutch control lever 106 is rotated in a clockwise direction 10 about the shaft 109 by the spring 110, causing the tab 112 on the arm 108 to move the clutch member 80 toward the right, thereby to engage the clutch plates 82 and 84.

The periphery of the cam member 95 is provided with a plurality of projections 95^a, which are spaced apart by intervening depressions 95^b. Associated with the cam member 95 is a lock control member 113 pivotally mounted upon a shaft 114 supported in a pair of spaced apart 25 brackets 115, carried by the base plate 28. The lock control member 113 is biased in a clockwise direction, as viewed from the left-hand end thereof, by a coil spring 116 extending between the lock control member 113 and the base plate 28. The lock control member 113 comprises a 30 forwardly extending locking edge 117, having such a thickness that it is adapted to engage any one of a plurality of notches 118 formed in the periphery of a locking disc 119 rigidly secured to the operating shaft 48; a rearwardly extending projection 120 adapted to ride upon the periphery of the cam member 95; and a forwardly extending locking arm 121 provided with a notch 121^a therein adapted to engage a 35 reduced annular portion 48^a on the operating shaft 48. The lock and clutch control mechanism 70 is so constructed and arranged that, as it is rotated step by step in a counter-clockwise direction, the projection 120 on the lock control 40 member 113 alternately engages one of the projections 95^a and one of the depressions 95^b, disposed about the periphery of the cam member 95. When the projection 120 engages one of the 45 projections 95^a, the lock control member 113 is rotated in a counter-clockwise direction about the shaft 114 against the bias of the spring 116, first causing the notch 121^a in the locking arm 121 to disengage the reduced annular portion 48^a on the operating shaft 48, thereby to release the 50 operating shaft 48 for movement in a longitudinal direction toward the left; and then causing the locking edge 117 of the lock control member 113 to engage one of the notches 118 formed in the periphery of the disc 119, thereby to lock the 55 operating shaft 48 against further rotational movement. On the other hand, when the projection 120 engages one of the depressions 95^b, the lock control member 113 is rotated in a clockwise direction about the shaft 114 by the spring 60 116, first causing the locking edge 117 of the lock control member 113 to disengage one of the notches 118 formed in the periphery of the disc 119, thereby to release the operating shaft 48 for rotational movement; and then causing the 65 notch 121^a in the locking arm 121 to engage the reduced annular portion 48^a on the operating shaft 48, thereby to lock the operating shaft 48 against movement in a longitudinal direction.

When the switching unit occupies an idle position, the operating shaft 48 is retained in its

normal angular position by the engagement between a stop 48^b carried by the operating member 48 and the guide bar 43 and in its normal longitudinal position by the engagement between the notch 121^a in the locking arm 121 and reduced annular portion 48^a on the operating shaft 48.

The arrangement of the cam members 94 and 95 on the shaft 96 of the lock and clutch control mechanism 70 is diagrammatically illustrated in Fig. 8. Referring to this figure, it will be observed that the finger 111 on the arm 107 of the clutch control member 106 engages one of the projections 94^a on the cam member 94, and the projection 120 on the lock control member 113 engages one of the depressions 95^b in the cam member 95, when the shaft 96 occupies its first angular position P1, corresponding to the idle position of the switching unit. During the course of the operation of the switching unit to select a particular line in the conductor bank 24, the shaft 96 of the lock and clutch control mechanism 70 is successively rotated into its second, third, and fourth angular positions P2, P3 and P4, respectively, causing the finger 111 successively to engage the same projection 94^a, the adjacent depression 94^b and the same depression 94^b; and causing the projection 120 successively to engage the adjacent projection 95^a, the same projection 95^a and the adjacent depression 95^b, in the respective angular positions of the shaft 96 of the lock and clutch control mechanism 70. In order to disengage the established connection to the selected line in the conductor bank 24 and to restore the operated switching unit to its idle position, the shaft 96 of the lock and clutch control mechanism 70 is rotated into its fifth angular position P5, corresponding to its first angular position P1, as is described more fully subsequently. In the fifth angular position P5, of the shaft 96 of the lock and clutch control mechanism 70, the finger 111 again engages a projection 94^a on the cam member 94, and the projection 120 again engages a depression 95^b in the cam member 95.

Referring now to the operation of the switching unit described, and assuming that the switching unit is to be operated to select a particular line from the conductor bank 24, such, for example, as the fourth line in the third subgroup or level, in the second group of lines in the conductor bank 24, it will be understood that the switching unit is controlled by a suitable impulse transmitter connected and arranged in a control circuit, including the operating motors 69 and 100. In order to cause the switching unit to operate and select the line noted above, the impulse device is first operated to transmit a first series of impulses, comprising two impulses, 50 thereby to cause the operating motor 69 to be energized two times successively. The elements of the switching unit are in the positions shown, corresponding to the idle position of the switching unit, at the beginning of the first series of 55 impulses. The clutch member 80 is rotated two steps in a counter-clockwise direction by the operating motor 69 through the pawl and ratchet wheel mechanism arranged therebetween, the ratchet wheel 75 being retained in its operated 60 position by a detent, not shown. At this time the lock and clutch control mechanism 70 occupies its first angular position P1, causing the clutch plates 81 and 83 to be in driving engagement, the operating shaft 48 to be locked against 65

movement in a longitudinal direction, and the operating shaft 48 to be released for rotational movement, as previously explained. Accordingly, the shaft 76 is rotated in a counter-clockwise direction against the bias of the spring 85, due to the engagement of the clutch plates 81 and 83; and the operating shaft 58 is not rotated, due to the disengagement of the clutch plates 82 and 84. The shaft 88 is rotated in a 5 clockwise direction by the shaft 76, due to the engagement of the gears 86 and 87, causing the spiral gear 91 to exert a force upon the cylindrical spiral gear 92, thereby tending simultaneously to rotate the operating shaft 48 in a counter-clockwise direction and to move the operating shaft 48 in a longitudinal direction. As previously noted, at this time, the operating shaft 48 is locked against movement in a longitudinal direction, but is free to be rotated. Thus, the 10 operating shaft 48 is rotated from its normal angular position into its second off-normal angular position, causing the projection 51^a on the cam member 51 to be moved into the slot 51^b, formed in the carriage 36 of the elementary switch 34 associated with the second group of lines in the conductor bank 24. When the cam projection 51^a is moved into the slot 51^b, formed 15 in the carriage 36 of the elementary switch 34, the elementary switch 34 is locked to the operating shaft 48 for movement in a longitudinal direction therewith. As previously explained, only the carriage of the elementary switch 34 is locked to the operating shaft 48 for movement in a longitudinal direction therewith, when the operating shaft 48 occupies its second off-normal angular position.

At the end of the first series of impulses, a single energizing impulse is transmitted to the operating motor 100. The shaft 96 of the lock and clutch control mechanism 70 is rotated one 20 step in a counter-clockwise direction into its second angular position P2, by the operating motor 100 through the pawl and ratchet wheel mechanism arranged therebetween, the ratchet wheel 93 being retained in its operated position by a detent, not shown. This rotation of the lock and clutch control mechanism 70 causes the projection 120 on the lock control member 113 to engage one of the projections 95^a on the cam member 95, thereby to rotate the lock control member 113 in a counter-clockwise direction against the bias of the spring 116. When the lock control member 113 is rotated in a counter-clockwise direction, the locking edge 117 of the lock control member 113 engages the second notch 118, formed 25 in the periphery of the disc 119, in order to lock the operating shaft 48 against further rotational movement. Also, the notch 121^a in the locking arm 121 disengages the reduced annular portion 30 48^a on the operating shaft 48, in order to release the operating shaft 48 for movement in a longitudinal direction toward the left. This rotation of the lock and clutch control mechanism 70 is not effective to rotate the clutch control lever 106, 35 as previously explained. Accordingly, the clutch plates 81 and 83 remain in engagement, at this time.

The impulse device is then operated to transmit a second series of impulses, comprising three impulses, thereby to cause the operating motor 69 to be energized three times successively. The clutch member 80 is rotated three steps further 40 in a counter-clockwise direction, thereby causing the spiral gear 91 to exert a force upon the cylindrical spiral gear 92, tending to rotate the operat-

ing shaft 48 in a counter-clockwise direction and to move the operating shaft 48 in a longitudinal direction toward the left, as previously explained. At this time, the operating shaft 48 is locked against rotational movement, but is free to be 5 moved in a longitudinal direction. Thus, the operating shaft 48 is moved from its normal longitudinal position into its third off-normal longitudinal position, causing the carriage of the selected elementary switch 34 to be moved against 10 the bias of the spring 55 into its third off-normal position corresponding to the third subgroup or level in the associated group of lines. As the carriage 36 of the selected elementary switch 34 is moved from its normal position into its first off-normal position, the teeth 61 provided on the flange 64 of the slide 37, carried by the carriage 36, are brought into engagement with the cylindrical gear 62, carried by the operating shaft 58. At this time, the operating shaft 48 is retained 15 in its second off-normal angular position by the lock and clutch control mechanism 70, and in its third off-normal longitudinal position by the engagement between the detent 54 pivotally mounted on the guide bar 43 and the ratchet 53 20 on the extreme right-hand end of the operating shaft 48. The carriage 36 of the operated elementary switch 34 is retained in its third off-normal position by the engagement between the projection 51^a on the cam member 51, carried by 25 the operating shaft 48, and the slot 51^b formed in the carriage 36.

At the end of the second series of impulses, a single energizing impulse is transmitted to the operating motor 100, causing the shaft 96 of the 30 lock and clutch control mechanism 70 to be rotated one step further in a counter-clockwise direction into its third angular position P3. This rotation of the shaft 96 of the lock and clutch control mechanism 70 causes the finger 111 on the 35 arm 107 of the clutch control lever 106 to engage one of the depressions 94^b in the periphery of the cam member 94, thereby to cause the spring 110 to rotate the clutch control lever 106 in a clockwise direction. When the clutch control lever 40 106 is rotated in a clockwise direction, the tab 112 on the arm 108 of the clutch control lever 106 moves the clutch member 80 toward the right, thereby to disengage the clutch plates 81 and 83 and to engage the clutch plates 82 and 84. This 45 rotation of the shaft 96 of the lock and clutch control mechanism 70 is not effective to rotate the lock control member 113, as previously explained. Accordingly, the operating shaft 48 remains 50 locked against rotational movement, at this time.

The impulse device is then operated to transmit a third series of impulses, comprising four impulses, thereby to cause the operating motor 69 to be energized four times successively. The clutch member 80 is rotated four steps further 55 in a counter-clockwise direction, thereby causing the operating shaft 58 to be rotated in a counter-clockwise direction from its normal position into its fourth off-normal position. Rotation of the operating shaft 58 into its fourth off-normal 60 position causes the slide 37, carried by the carriage 36 of the operated elementary switch 34 to be moved into its fourth off-normal position, thereby to establish connections between the pairs of contact members 39 and 40, and the positive 65 and negative conductors, respectively, of the fourth line in the previously selected subgroup or level of lines. When the slide 37 is moved into its first off-normal position, the flange 64 thereon is moved into engagement with the third 70

notch formed in the locking bar 37^a, individual to the elementary switch 34, thereby to retain the carriage 36 of the elementary switch 34 in its third off-normal position independently of the position of the operating shaft 48. Also, at this time, a lug, not shown, carried by the operating shaft 58, engages the detent 54 pivotally mounted on the guide bar 43, causing the detent 54 to be moved out of engagement with the rack 53 in order to release the operating shaft 48 for movement in a longitudinal direction. The operating shaft 48 is restrained against movement in a longitudinal direction by the engagement between the projection 51^a on the cam member 51 and the slot 51^b formed in the carriage 36, at this time. At this time, in the operated elementary switch 34, the carriage 36 is retained in its third off-normal position by the locking bar 37^a, and the slide 37 is held in its fourth off-normal position by the clutch member 80.

At the end of the third series of impulses, a single energizing impulse is transmitted to the operating motor 100, causing the shaft 96 of the lock and clutch control mechanism 70 to be rotated one step further in a counter-clockwise direction into its fourth angular position P4. This rotation of the shaft 96 of the lock and clutch control mechanism 70 causes the projection 120 on the lock control member 113 to engage one of the depressions 95^b in the cam member 95, thereby to cause the spring 116 to rotate the lock control member 113 in a clockwise direction. When the lock control member 113 is rotated in a clockwise direction, the locking edge 117 thereof disengages the second notch 118 formed in the periphery of the disc 119 in order to release the operating shaft 48 for rotational movement. Also, the notch 121^a in the locking arm 121 is moved into a position wherein it may engage the reduced annular portion 48^a on the operating shaft 48, when the operating shaft 48 is returned to its normal longitudinal position. The operating shaft 48 is then rotated in a clockwise direction back into its normal angular position, by the spring 85 through the gears 86 and 87, the spiral gear 91, and the cylindrical spiral gear 92, the operating shaft 48 being arrested in its normal angular position by the engagement between the stop 48^b carried by the operating shaft 48 and the guide bar 43. The operating shaft 48 is then moved in a longitudinal direction toward the right back into its normal longitudinal position by the spring 85 through the gears 86 and 87, the spiral gear 91, and the cylindrical spiral gear 92. When the operating shaft 48 is moved back into its normal longitudinal position, the notch 121^a in the locking arm 121 engages the reduced annular portion 48^a in the operating shaft 48, thereby to lock the operating shaft 48 against movement in a longitudinal direction. Thus, the operating shaft 48 is restored to its normal position corresponding to the idle position of the switching unit. This rotation of the shaft 96 of the lock and clutch control mechanism 70 is not effective to rotate the clutch control lever 106, as previously explained. Accordingly, the clutch plates 82 and 84 remain in engagement, at this time.

In order to interrupt the established connection to the particular selected line in the conductor bank 24 and to restore the switching unit to its idle position, it is only necessary to transmit a single energizing impulse to the operating motor 100, thereby causing the shaft 96 of the lock and clutch control mechanism 70 to be ro-

tated one step further in a counter-clockwise direction into its fifth angular position P5, which angular position corresponds to its first angular position P1. This rotation of the shaft 96 of the lock and clutch control mechanism 70 causes the finger 111 on the arm 107 of the clutch control lever 106 to engage one of the projections 94^a on the cam member 94, thereby to rotate the clutch control lever 106 in counter-clockwise direction against the bias of the spring 110. When the clutch control lever 106 is rotated in a counter-clockwise direction, the tab 112 on the arm 108 of the clutch control lever 106 moves the clutch member 80 toward the left, thereby to disengage the clutch plates 82 and 84 and to engage the clutch plates 81 and 83. When the clutch plates 82 and 84 are disengaged, the operating shaft 58 is rotated in a clockwise direction back into its normal position by the spring 68. This rotation of the operating shaft 58 causes the slide 37 of the operated elementary switch 34 to be moved back into its normal position through the driving engagement between the cylindrical gear 62 and the teeth 67 provided on the flange 64 on the slide 37. When the slide 37 is moved back into its normal position, the flange 64 thereon disengages the third notch in the locking bar 37^a, individual to the elementary switch 34, thereby to release the carriage 36 for movement in a longitudinal direction. The spring 55, individual to the elementary switch 34, then moves the carriage 36 back into its normal position. This rotation of the shaft 96 of the lock and clutch control mechanism 70 is not effective to rotate the lock control member 113, as previously explained. Accordingly, at this time, the operating shaft 48 remains locked against movement in a longitudinal direction. Thus, the switching unit is completely restored to its idle position and is again in condition to be reoperated to select any particular line in the conductor bank 24.

While there has been described what is at present considered to be the preferred embodiment of the invention, it will be understood that various modifications may be made in the structure thereof, and it is intended in the appended claims to cover all such modifications as fall within the true spirit and scope of the invention.

What is claimed is:

1. An automatic switching unit comprising a plurality of elementary switches; each of said elementary switches including a carriage movable in a first direction, an element carried by said carriage and movable in a second direction, and a contact controlling member carried by said element; means for selecting any one of said elementary switches to be operated; means including a first operating member common to said elementary switches for moving the carriage of a selected one of said elementary switches; means including a second operating member common to said elementary switches for moving the element of said selected elementary switch; and means for moving successively said first and said second operating members.

2. An automatic switching unit comprising a plurality of elementary switches; each of said elementary switches including a carriage movable in a first direction, an element carried by said carriage and movable in a second direction, and a contact controlling member carried by said element; means for selecting any one of said elementary switches to be operated; a first operating member common to said elementary switches and supported for step-by-step movement;

means responsive to the step-by-step movement of said first operating member for moving the carriage of a selected one of said elementary switches step by step in said first direction; a second operating member common to said elementary switches and supported for step-by-step movement; and means responsive to the step-by-step movement of said second operating member for moving the element of said selected elementary switch step by step in said second direction.

3. An automatic switching unit comprising a plurality of elementary switches; each of said elementary switches including a carriage movable in a first direction, an element carried by said carriage and movable in a second direction, and a contact controlling member carried by said element; means including a first operating member common to said elementary switches for selecting any one of said elementary switches to be operated and for moving the carriage of a selected one of said elementary switches; and means including a second operating member common to said elementary switches for moving the element of said selected elementary switch.

4. An automatic switching unit comprising a plurality of elementary switches; each of said elementary switches including a carriage movable in a first direction, an element carried by said carriage and movable in a second direction, and a contact controlling member carried by said element; a first operating member common to said elementary switches and movable in two directions; means controlled by the movement of said first operating member in one of said directions for selecting any one of said elementary switches to be operated; means responsive to the movement of said first operating member in the other of said directions for moving the carriage of a selected one of said elementary switches; and means including a second operating member common to said elementary switches for moving the element of said selected elementary switch.

5. An automatic switching unit comprising a plurality of elementary switches; each of said elementary switches including a carriage movable in a first direction, an element carried by said carriage and movable in a second direction, and a contact controlling member carried by said element; a first operating member common to said elementary switches and supported for both rotational and longitudinal movements; means controlled by the rotational movement of said first operating member for selecting any one of said elementary switches to be operated; means responsive to the longitudinal movement of said first operating member for moving the carriage of a selected one of said elementary switches; a second operating member common to each of said switches and supported for rotational movement; and means responsive to the rotational movement of said second operating member for moving the element of said selected elementary switch.

6. An automatic switching unit comprising a plurality of elementary switches; each of said elementary switches including a carriage movable in a first direction, an element carried by said carriage and movable in a second direction, and a contact controlling member carried by said element; a first operating member common to said elementary switches and movable step by step in two directions; means controlled by the movement of said first operating member step by step in one of said directions for selecting suc-

cessively said elementary switches to be operated; means responsive to the movement of said first operating member step by step in the other of said directions for moving the carriage of a selected one of said elementary switches step by step in said first direction; a second operating member common to said elementary switches and movable step by step; and means responsive to the movement of said second operating member step by step for moving the element of said selected switch step by step in said second direction.

7. An automatic switching unit comprising a plurality of elementary switches; each of said elementary switches including a carriage movable in a first direction, an element carried by said carriage and movable in a second direction, and a contact controlling member carried by said element; a first operating member common to said elementary switches and supported for both rotational and longitudinal step-by-step movements; means controlled by the rotational step-by-step movement of said first operating member for selecting successively said elementary switches to be operated, means responsive to the longitudinal step-by-step movement of said first operating member for moving the carriage of a selected one of said switches step by step in said first direction; a second operating member common to said elementary switches and supported for rotational step-by-step movement; and means responsive to the rotational step-by-step movement of said second operating member for moving the element of said selected elementary switch step by step in said second direction.

8. An automatic switching unit comprising a plurality of elementary switches; each of said elementary switches including a carriage movable in a first direction, an element carried by said carriage and movable in a second direction, and a contact controlling member carried by said element; an operating member common to said elementary switches and movable in two directions; means controlled by the movement of said operating member in one of said directions for selecting any one of said elementary switches to be operated; means responsive to the movement of said operating member in the other of said directions for moving the carriage of a selected one of said elementary switches; a mechanism operable to move said operating member in each of said directions; means including a locking mechanism for controlling the directions of movement of said operating member; and means for moving the element of said selected elementary switch.

9. An automatic switching unit comprising a plurality of elementary switches; each of said elementary switches including a carriage movable in a first direction, an element carried by said carriage and movable in a second direction, and a contact controlling member carried by said element; an operating member common to said elementary switches and movable in two directions; means controlled by the movement of said operating member in one of said directions for selecting any one of said elementary switches to be operated; means responsive to the movement of said operating member in the other of said directions for moving the carriage of a selected one of said elementary switches; an operating mechanism tending to move said operating member in each of said directions simultaneously; means including a locking mechanism adapted alternately

to lock said first operating member against movement in one and the other of said directions for controlling the directions of movement of said operating member; and means for moving the element of said selected elementary switch.

10. An automatic switching unit comprising a plurality of elementary switches; each of said elementary switches including a carriage movable in a first direction, an element carried by said carriage and movable in a second direction, and a contact controlling member carried by said element; an operating member common to said elementary switches and supported for both rotational and longitudinal movements; means controlled by the rotational movement of said operating member for selecting any one of said elementary switches to be operated; means responsive to the longitudinal movement of said operating member for moving the carriage of a selected one of said elementary switches; a mechanism including a cylindrical spiral gear carried by said operating member and operable to impart to said operating member both rotational and longitudinal movements; means including a locking mechanism for controlling the movements imparted to said operating member; and means for moving the element of said selected elementary switch.

11. An automatic switching unit comprising a plurality of elementary switches; each of said elementary switches including a carriage movable in a first direction, an element carried by said carriage and movable in a second direction, and a contact controlling member carried by said element; a first operating member common to said elementary switches and supported for both rotational and longitudinal step-by-step movements; means controlled by the rotational step-by-step movement of said first operating member for selecting successively said elementary switches to be operated; means responsive to the longitudinal step-by-step movement of said first operating member for moving the carriage of a selected one of said switches step by step in said first direction; a mechanism operable to impart to said first operating member both rotational and longitudinal step-by-step movements; means including a locking mechanism for controlling the movements imparted to said first operating member; a second operating member common to said elementary switches and supported for rotational step-by-step movement; and means responsive to the rotational step-by-step movement of said second operating member for moving the element of said selected elementary switch step by step in said second direction.

12. An automatic switching unit comprising a plurality of elementary switches; each of said elementary switches including a carriage movable in a first direction, an element carried by said carriage and movable in a second direction, and a contact controlling member carried by said element; a first operating member common to said elementary switches and movable step by step in two directions; means controlled by the movement of said first operating member step by step in one of said directions for selecting successively said elementary switches to be operated; means responsive to the movement of said first operating member step by step in the other of said directions for moving the carriage of a selected one of said elementary switches step by step in said first direction; a mechanism operable to move said first operating member step by step in each of said directions; means including a lock-

ing mechanism for controlling the directions of movement of said first operating member; a second operating member common to said elementary switches and movable step by step; and means responsive to the movement of said second operating member step by step for moving the element of said selected elementary switch step by step in said second direction. 5

13. An automatic switching unit comprising a plurality of elementary switches; each of said elementary switches including a carriage movable in a first direction, an element carried by said carriage and movable in a second direction, and a contact controlling member carried by said element; a first operating member common to said elementary switches and movable in two directions; means controlled by the movement of said first operating member in one of said directions for selecting any one of said elementary switches to be operated; means responsive to the movement of said first operating member in the other of said directions for moving the carriage of a selected one of said elementary switches; a mechanism operable to move said first operating member in each of said directions; a locking mechanism operable to control the directions of movement of said first operating member, said locking mechanism normally being operated to release said first operating member to be moved in said first direction and to lock said first operating member against movement in said other direction and being operated in response to the movement of said first operating member in said one direction to release said first operating member to be moved in said other direction and to lock said first operating member against further movement in said one direction; and means including a second operating member common to said elementary switches for moving the element of said selected elementary switch. 40

14. An automatic switching unit comprising a plurality of elementary switches; each of said elementary switches including a carriage movable in a first direction, an element carried by said carriage and movable in a second direction, and a contact controlling member carried by said element; a first operating member common to said elementary switches and movable in two directions; means controlled by the movement of said first operating member in one of said directions for locking the carriages of said elementary switches to said first operating member selectively and in a predetermined order, thereby to cause the carriage of a selected one of said elementary switches to be moved in said first direction when said first operating member is moved in the other of said directions; and means including a second operating member common to said elementary switches for moving the element of said selected elementary switch in said second direction. 50

15. An automatic switching unit comprising a plurality of elementary switches; each of said elementary switches including a carriage movable in a first direction, an element carried by said carriage and movable in a second direction, and a contact controlling member carried by said element; a first operating member common to said elementary switches and supported for both rotational and longitudinal step-by-step movements; means controlled by the rotational step-by-step movement of said first operating member for locking the carriages of said elementary switches to said first operating member selectively and in a predetermined order, thereby to cause the carriage of a selected one of said elementary switches to be moved in said first direction when said first operating member is moved in the other of said directions; and means including a second operating member common to said elementary switches for moving the element of said selected elementary switch in said second direction. 60

- switches to be moved step by step in said first direction when said first operating member is moved longitudinally step by step; a second operating member common to said elementary switches and supported for step-by-step movement; and means responsive to the step-by-step movement of said second operating member for moving the element of said selected elementary switch step by step in said second direction.
- 10 16. An automatic switching unit comprising a plurality of elementary switches; each of said elementary switches including a movable carriage, a movable element carried by said carriage, and a contact controlling member carried by said element; a first movable member common to said switches; means for locking selectively and in a predetermined order the carriages of said elementary switches to said first member, thereby to cause the carriage of a selected one of said elementary switches to be locked to said first member for movement with said first member; and means including a second movable member common to said elementary switches for moving the element of said selected elementary switch.
- 15 17. An automatic switching unit comprising a plurality of elementary switches; each of said elementary switches including a movable carriage, a movable element carried by said carriage, and a contact controlling member carried by said element; a movable operating member common to said elementary switches; a plurality of first parts carried by said operating member; a second part carried by the carriage of each one of said elementary switches and associated with a corresponding one of said first parts; means for moving selectively corresponding ones of said first and second parts into engagement; means for locking engaging ones of said first and second parts in engagement, thereby to lock the carriage of the corresponding one of said elementary switches to said operating member for movement therewith; and means for moving the element of said corresponding one of said elementary switches.
- 20 18. An automatic switching unit comprising a plurality of elementary switches; each of said elementary switches including a movable carriage, a movable element carried by said carriage, and a contact controlling member carried by said element; a movable operating member common to said elementary switches; a plurality of first parts carried by said operating member; a second part carried by the carriage of each one of said elementary switches and associated with a corresponding one of said first parts; corresponding ones of said first and second parts constituting sets of parts; means for moving selectively and in a predetermined order said sets of parts into engagement; said sets of parts being so constructed and arranged that only one set of parts can be moved into engagement at any time; means for locking the parts of any one of the engaging sets of parts in engagement, thereby to lock the carriage of the corresponding one of said elementary switches to said operating member for movement therewith; and means for moving the element of said corresponding one of said elementary switches.
- 25 19. An automatic switching unit comprising a plurality of elementary switches; each of said elementary switches including a carriage supported for longitudinal movement, an element carried by said carriage and supported for lateral movement, and a contact controlling member carried by said element; a first operating member common to said elementary switches and supported for both rotational and longitudinal movements; means controlled by the rotational movement of said first operating member for locking the carriages of said elementary switches to said first operating member selectively and in a predetermined order, thereby to cause the carriage of a selected one of said elementary switches to be locked to said first operating member for movement longitudinally with said first operating member; and means including a second operating member common to said elementary switches for moving the element of said selected elementary switch laterally.
- 30 20. An automatic switching unit comprising a plurality of elementary switches; each of said elementary switches including a carriage supported for longitudinal movement, an element carried by said carriage and supported for lateral movement, and a contact controlling member carried by said element; a first operating member common to said elementary switches and supported for both rotational and longitudinal movements; a plurality of cam members carried by said first operating member, each of said cam members being associated with a corresponding one of said elementary switches and provided with a first part adapted to drive a cooperating second part carried by the carriage of the associated elementary switch, said cam members being so constructed and arranged that said first parts are brought selectively and in a predetermined order into driving relationship with said cooperating second parts as said first operating member is rotated, thereby to cause the carriage of a selected one of said elementary switches to be locked to said first operating member for movement longitudinally with said first operating member; and means including a second operating member common to said elementary switches for moving the element of said selected elementary switch laterally.
- 35 21. An automatic switching unit comprising a plurality of elementary switches; each of said elementary switches including a carriage movable in a first direction, a slide carried by said carriage and movable in a second direction, said slide being provided with a rack, and a contact controlling member carried by said slide; a first operating member common to said elementary switches and movable in two directions; means controlled by the movement of said first operating member in one of said directions for selecting one of said elementary switches to be operated; means responsive to the movement of said first operating member in the other of said directions for moving the carriage of said selected elementary switch in said first direction; a second operating member common to said elementary switches and supported for rotational movement; a plurality of gears carried by said second operating member, each of said gears being associated with a corresponding one of said elementary switches and adapted to engage the rack provided on the slide of the associated elementary switch; means responsive to the movement of the carriage of said selected switch in said first direction for moving the rack provided on the slide of said selected elementary switch and the associated gear carried by said second operating member into engagement; and means for rotating said second operating member, thereby to cause the slide of said selected elementary switch to be moved in said second direction.
- 40 22. An automatic switching unit comprising

- a plurality of elementary switches; each of said elementary switches including a carriage movable in a longitudinal direction, a slide carried by said carriage and movable in a lateral direction, said slide being provided with a rack, and a contact controlling member carried by said slide; a first operating shaft common to said elementary switches and supported for both rotational and longitudinal step-by-step movements; 5
- 10 a plurality of cam members carried by said first operating shaft, each of said cam members being associated with a corresponding one of said elementary switches and provided with a first part adapted to drive a cooperating second part carried by the carriage of the associated elementary switch, said cam members being so constructed and arranged that said first parts are brought successively into driving relationship with said cooperating second parts as said first operating shaft is rotated step by step, thereby to select successively said elementary switches to be operated; means for rotating said first operating shaft a predetermined number of steps, thereby to select a corresponding one of said elementary switches to be operated; means for moving said first operating shaft longitudinally a predetermined number of steps, thereby to move the carriage of said selected elementary switch step by step in said longitudinal direction; a second operating shaft common to said elementary switches and supported for rotational step-by-step movement; a plurality of gears carried by said second operating shaft, each of said gears being associated with a corresponding one of said elementary switches and adapted to engage the rack provided on the slide of the associated elementary switch after the associated elementary switch has been selected to be operated and the carriage thereof has been moved in said longitudinal direction; and means for rotating said second operating shaft a predetermined number of steps, thereby to move the slide of said selected elementary switch step by step in said lateral direction.
- 45 23. An automatic switching unit comprising a plurality of elementary switches; each of said elementary switches including a carriage movable in a first direction, an element carried by said carriage and movable in a second direction, and a contact controlling member carried by said element; a first operating member common to said elementary switches and supported for both rotational and longitudinal movements; means controlled by the rotational movement of said first operating member for selecting one of said elementary switches to be operated; means responsive to the longitudinal movement of said first operating member for moving the carriage of said selected elementary switch; a second operating member common to each of said switches and supported for rotational movement; means responsive to the rotational movement of said second operating member for moving the element of said selected elementary switch; a mechanism selectively operable to impart to said first operating member both rotational and longitudinal movements and to impart to said second operating member rotational movement; means for controlling the selective operations of said mechanism; and means including a locking mechanism for controlling the movements imparted to said first operating member.
- 70 24. An automatic switching unit comprising a plurality of elementary switches; each of said elementary switches including a carriage mov-
- able in a first direction, an element carried by said carriage and movable in a second direction, and a contact controlling member carried by said element; a first operating member common to said elementary switches and supported for both 5 rotational and longitudinal step-by-step movements; means controlled by the rotational step-by-step movement of said first operating member for selecting successively said elementary switches to be operated; means responsive to the longitudinal step-by-step movement of said first operating member for moving the carriage of a selected one of said switches step by step in said first direction; a second operating member common to said elementary switches and supported for rotational step-by-step movement; means responsive to the rotational step-by-step movement of said second operating member for moving the element of said selected elementary switch step by step in said second direction; a mechanism adapted to be connected selectively to said first operating member and to said second operating member, said mechanism being operable to impart to said first operating member both rotational and longitudinal step-by-step movements and to impart to said second operating member rotational step-by-step movement; means for controlling selectively the connections of said mechanism; and means including a locking mechanism for controlling the movements imparted to said first operating member.
- 75 25. A switch comprising, in combination, a carriage movable in a first direction, an element carried by said carriage and movable in a second direction, a contact controlling member carried by said element, a fixed locking member normally engaging said element, thereby to lock said element against movement in said second direction, means for moving said carriage and said element carried thereby in said first direction, said element and said fixed locking member being so constructed and arranged that they are automatically disengaged when said element is moved with said carriage in said first direction, thereby to unlock said element for movement in said second direction, and means for moving said element in said second direction.
26. A switch comprising, in combination, a carriage movable in a first direction, an element carried by said carriage and movable in a second direction, a contact controlling member carried by said element, a movable locking member carried by said element, a fixed locking member, said locking members normally being in engagement, thereby to lock said element against movement in said second direction, means for moving said carriage and said element carried thereby in said first direction, said locking members being so constructed and arranged that they are automatically moved into disengagement when said element is moved with said carriage in said first direction, thereby to unlock said element for movement in said second direction, and means for moving said element in said second direction, said members being moved into engagement when said element is moved in said second direction, thereby to lock said carriage and said element carried thereby against further movement in said first direction.
27. A switch comprising, in combination, a carriage movable in a first direction, an element carried by said carriage and movable in a second direction, a contact controlling member carried by said element, a movable locking member carried by said element, a fixed locking member, one

- of said locking members having an opening therein into which the other of said locking members is adapted to be inserted, said locking members normally being in engagement, thereby 5 to lock said element against movement in said second direction, means for moving said carriage and said element carried thereby in said first direction, the opening in said one locking member and said other locking member being moved 10 into alignment when said element is moved with said carriage in said first direction, thereby to unlock said element for movement in said second direction, and means for moving said element in said second direction, said other locking member being inserted into the opening in said one locking member and said locking members being moved into engagement when said element is moved in said second direction, thereby to lock 15 said carriage and said element carried thereby against further movement in said first direction. 20
28. A switch comprising, in combination, a carriage movable along a first path and having a normal position, an element carried by said carriage, said element being movable along a second path and having a normal position, a contact controlling member carried by said element, means for locking said element in its normal position, means for advancing said carriage from its normal position along said first path, means 25 responsive to the movement of said carriage from its normal position for unlocking said element for movement along said second path, means for advancing said element from its normal position along said second path, means responsive to the movement of said element from its normal 30 position for locking said carriage against further movement along said first path, means for retracting said element along said second path to its normal position, means responsive to the movement of said element to its normal position for unlocking said carriage for movement along said first path, and means for retracting said carriage along said first path to its normal 35 position.
45. 29. An automatic switching unit comprising a plurality of elementary switches; each of said elementary switches including a carriage movable in a first direction, an element carried by said carriage and movable in a second direction, and a contact controlling member carried by said element; means for selecting any one of said elementary switches to be operated; means for moving the carriage of a selected one of said elementary switches; normally ineffective means 50 for moving the element of said selected elementary switch; and means controlled by the movement of the carriage of said selected elementary switch for rendering said last-mentioned means effective. 55
60. 30. An automatic switching unit comprising a plurality of elementary switches; each of said elementary switches including a carriage movable in a first direction, an element carried by said carriage and movable in a second direction, and a contact controlling member carried by said element; means for selecting any one of said elementary switches to be operated; means including a first operating member common to said elementary switches for moving the carriage of a selected one of said elementary switches; means including a second operating member common to said elementary switches for moving the element of said selected elementary switch; means controlled by the 65 movement of the carriage of said selected elementary switch for rendering said last-mentioned means effective. 70
75. 31. In a switching system including a contact bank; a plurality of switching units commonly associated with said contact bank; each of said switching units comprising a plurality of elementary switches; each of said elementary switches including a carriage movable in a first direction with respect to said contact bank, an element carried by said carriage and movable in a second direction with respect to said contact bank, and a contact controlling member carried by said element; means for selecting any one of said elementary switches to be operated; and means for moving the carriage and the element of a selected one of said elementary switches. 20
32. In a switching system including a contact bank; a switching unit associated with said contact bank; said switching unit comprising a plurality of independently operable elementary switches; each of said elementary switches including a carriage movable in a first direction with respect to said contact bank, an element carried by said carriage and movable in a second direction with respect to said contact bank, and a contact controlling member carried by said element; and impulse responsive means for selecting any one of said elementary switches to be operated and for moving the carriage and the element of a selected one of said elementary switches. 25
33. In a switching system including a contact bank; a plurality of switching units commonly associated with said contact bank; each of said switching units comprising a plurality of elementary switches; each of said elementary switches including a carriage movable in a first direction with respect to said contact bank, an element carried by said carriage and movable in a second direction with respect to said contact bank, and a contact controlling member carried by said element; means for selecting any one of said elementary switches to be operated; means including a first operating member common to said elementary switches for moving the carriage of a selected one of said elementary switches; and means including a second operating member common to said elementary switches for moving the element of said selected elementary switch. 30
34. In a switching system including a contact bank; a plurality of switching units commonly associated with said contact bank; each of said switching units comprising a plurality of elementary switches; each of said elementary switches including a carriage movable in a first direction with respect to said contact bank, an element carried by said carriage and movable in a second direction with respect to said contact bank, and a contact controlling member carried by said element; means for selecting any one of said elementary switches to be operated; means including a first operating member common to said elementary switches for moving the carriage of a selected one of said elementary switches; means including a second operating member common to said elementary switches for moving the element of said selected elementary switch; and motor means for moving successively said first and said second operating members. 35
35. In a switching system including a contact 40

- bank divided into a plurality of groups of contacts; a plurality of switching units commonly associated with said contact bank; each of said switching units being operable independently of the other of said switching units and comprising a plurality of independently operable elementary switches respectively associated with the groups of contacts in said contact bank; each of said elementary switches including a carriage movable in a first direction with respect to said contact bank, an element carried by said carriage and movable in a second direction with respect to said contact bank, and a contact controlling member carried by said element and cooperating with the contacts in the associated group of contacts in said contact bank; means for selecting any one of said elementary switches to be operated; and means for moving the carriage and the element of a selected one of said elementary switches.
36. In a switching system including a contact bank divided into a plurality of groups of contacts; a switching unit associated with said contact bank; said switching unit comprising a plurality of independently operable elementary switches respectively associated with the groups of contacts in said contact bank; each of said elementary switches including a carriage movable in a first direction with respect to said contact bank, an element carried by said carriage and movable in a second direction with respect to said contact bank, and a contact controlling member carried by said element and cooperating with the contacts in the associated group of contacts in said contact bank; and impulse responsive means for selecting any one of said elementary switches to be operated and for moving the carriage and the element of a selected one of said elementary switches.
37. In a switching system including a contact bank divided into a plurality of groups of contacts; a switching unit associated with said contact bank; said switching unit comprising a plurality of independently operable elementary switches respectively associated with the groups of contacts in said contact bank; each of said elementary switches being operative to control the contacts in the associated group of contacts in said contact bank; means for selecting any one of said elementary switches to be operated and for preventing the operation of the other of said elementary switches; and means for selectively controlling the operation of said selected elementary switch.
38. In a switching system including a longitudinally extending contact bank and a frame associated therewith; a plurality of self-contained switching units removably supported by said frame in spaced-apart relationship and commonly associated with said contact bank; each of said switching units being operable independently of the other of said switching units and comprising a plurality of independently operable elementary switches; each of said elementary switches including a carriage movable in a first direction with respect to said contact bank, an element carried by said carriage and movable in a second direction with respect to said contact bank, and a contact controlling member carried by said element; means for selecting any one of said elementary switches to be operated; and means for moving the carriage and the element of a selected one of said elementary switches.
39. In a switching system including a longitudinally extending contact bank divided into a plurality of groups of contacts and a frame associated therewith; a plurality of self-contained switching units removably supported by said frame in spaced-apart relationship and commonly associated with said contact bank; each of said switching units being operable independently of the other of said switching units and comprising a plurality of independently operable elementary switches respectively associated with the groups of contacts in said contact bank; each of said elementary switches being operative to control the contacts in the associated group of contacts in said contact bank; means for selecting any one of said elementary switches to be operated and for preventing the operation of the other of said elementary switches; and means for selectively controlling the operation of said selected elementary switch.
40. In a switching system including a contact bank; a switching unit associated with said contact bank; said switching unit comprising a plurality of independently operable elementary switches; each of said elementary switches including a carriage movable in a first direction with respect to said contact bank, an element carried by said carriage and movable in a second direction with respect to said contact bank, and a contact controlling member carried by said element; impulse responsive means operative successively to select any one of said elementary switches to be operated, to move the carriage of a selected one of said elementary switches, and to move the element of a selected one of said elementary switches; and additional impulse responsive means for controlling the operation of said first-mentioned impulse responsive means.
41. In a switching system including a contact bank divided into a plurality of groups of contacts; a switching unit associated with said contact bank; said switching unit comprising a plurality of elementary switches respectively associated with the groups of contacts in said contact bank; each of said elementary switches being operative independently of the other of said elementary switches to control the contacts in the associated group of contacts in said contact bank; impulse responsive means operative successively to select any one of said elementary switches to be operated, and selectively to control the operation of said selected elementary switch; and additional impulse responsive means for controlling the operation of said first-mentioned impulse responsive means.
